his ATTORNEY

UNITED STATES PATENT OFFICE

MATTHEW M. FRIEDEMANN, OF NEW YORK, N. Y.

DISPLAY ASSEMBLY

Application filed May 29, 1928. Serial No. 281,408.

This invention relates generally to display fixtures, and is particularly applicable for purposes of merchandising wares in show cases, show windows, stores or the like, to serve window dressers in displaying the merchandise to best advantage and attractively arrange the merchandise in an appealing manner to prospective buyers.

My invention has for an object thereof the provision of a display device which is readily adaptable to periodic changes of display customarily resorted to by window dressers and suitable for arranging merchandise of different size and form, depending upon the merchandise desired to be featured in the display area and in which variation may be made with the minimum number of fixtures and without particularly constructing the display fixture for any type of merchandise.

20 Thus, more specifically, my invention has for an object thereof the provision of a display fixture whereby shelves may be assembled in combination with a standard and variably positioned along the length thereof to accommodate the same for best display purposes or increase or decrease the number of shelves so arranged in accordance with the nature of the merchandise displayed as to its size and other general characteristics.

30 Still more specifically, my invention has for an object thereof the provision of a display device including a standard with which there is adapted to be associated display shelves angularly adjustable therewith and variably positioned along its length, as well as any numbers thereof, and which adjustment and position of the shelves thereof may be made independently of each other and whereby the display area may be built up and increased or decreased to suit the taste of the window dresser or to adapt the same to the particular merchandise desired to be displayed without adversely affecting the ornamental display, and capable of adapting the same to show cases or store windows of different sizes.

35 Still more specifically, my invention has for an object thereof the provision of a display standard which may be built up to any desired length and which is suitable for use

with a movable fixture or stand or which may be used as a support in a store window or show case. My invention contemplates the provision of a standard suitable for use with a display device such as set forth in the Patent No. 1,554,137 and with the display holders therein disclosed wherein a display holder or shelf may be positioned angularly or relatively longitudinally along the length of any standard, and for the purpose of including any number of display holders or shelves, my invention contemplates the provision of a standard or support construction which may be built up to accommodate the same for assembling therewith any number of said display holders or shelves and which is suitable for use with a store window, show case or which may be assembled with a base to serve as a display fixture in any desired relationship.

40 To attain these objects and such further objects as may appear herein or be herein-after pointed out, I make reference to the drawing forming a part hereof, in which—

45 Figure 1 is a perspective view showing our assembly;

50 Figure 2 is an enlarged perspective view of a joint, separated to disclose the manner of assembly;

55 Figure 3 is an enlarged perspective view of a modification corresponding to that shown in Figure 2;

60 Figure 4 is a section taken on a line corresponding to the line 4—4 in Figure 3 with an adjacent complementary section shown assembled therewith.

65 Referring to the drawing, it will be observed that in Figure 1 I have shown a general assembly of the display fixture including a standard 10 which preferably includes side walls of sheet metal 11 and 12, perforated along its length with a plurality of openings 13 arranged to engage and support display shelf supporting members 14, which include a standard embracing portion 15 corresponding in shape to that of the cross sectional configuration of the standard.

70 As described in the patent aforementioned, the display shelf supporting members or elements are held in position by the engaging

pins of the arms 16 passing through the standard embracing portion and the brace arm 17. Inwardly turned pins from these members 16 and 17 engage with the perforations 13 to hold the display supporting member and shelf elements thereon in predetermined angular relationship with the standard.

The standard 10 with the shelf elements thereon may be used in any relationship as a display fixture and for this purpose the side walls of the standard have formed at their lower terminal portion extended ears 18, 19, disposed laterally from the walls 11 and 12 respectively. An extension or ear portion 20 forms a continuation of the intermediate wall 11'. These extension ears 18, 19 and 20 are preferably integral with the walls of the standard and in this manner admirably serve to rigidly hold the standard in relation to any base, such as 21, by passing screw members 22 through these ear portions. It will be observed that when so combined the standard 10 and its supporting base 21 form a separable and individual display fixture movable about at will and capable of being positioned as desired. It will be observed, however, that the standard 10 with its extension ears may be attached to any other base material, which may be the bottom wall of a show case or the floor of a show window, forming a permanent fixture with the show case or store window, if so desired.

It will be observed that the standard 10 may have combined therewith a plurality of display shelf elements along the length thereof. However, to produce certain ornamental effects in display and to increase the display area, the standard 10 may have combined therewith an extension or complementary section 10'. This complementary section 10', as well as the main standard 10, is preferably recessed and for this purpose it is preferred to make the members 10 and 10' tubular and square in cross sectional area. This tubular construction permits the joining of the standard and the extension complementary section by inserting in the recess portion a filler member or block 23, portions of which are disposed in the upper end of the standard 10, the other portion thereof being disposed within the recess of the complementary section 10'.

For assembling and joining the standard 10 and the complementary section 10' the filler member or block 23 is inserted in the upper end of the standard and held in position by the screw members 23' passing through the perforations 24 provided in the side walls 11' and 12', engaging the filler member or block to rigidly hold the same in position. It is preferred to have this filler member or block 23 of such size within the recesses of the standard and the complementary section so as to be frictionally held therein so that pre-

liminary adjustment may be made to join the sections 10 and 10' when these sections are intended to be combined or assembled. For connecting the sections 10 and 10', screw members 23'' are passed through the apertures 24 in the complementary section 10' to engage the filler member or block 23 in the screw holders 24', more clearly shown in Figure 2. In this manner the frictional bond between the filler block and the recesses of the standard and the complementary section, as well as the screw engagement, serves to rigidly assemble these parts for forming an extended member with the walls 11 and 12 and the perforations thereon continuous so that a display shelf element may be moved along the length of the extended standard without any interference whatsoever.

Where I have used a filler block or member as shown in Figure 2 it is preferred to form this block at those faces adjacent the perforations 13 with clearance slots 25 so that the pins of the members 16 and 17 may be adjusted as desired, even at a point adjacent the joint formed between the members 10 and 10'. Thus, a display shelf element may be moved and adjusted along the length of the combined sections formed by the standards 10 and the complementary sections 10' without interference due to the joint at the terminal of the standard 10, the capacity of the standard thereby being increased to hold the support display shelf elements in accordance with the length of the complementary section 10'. It will be observed that though I have shown only a single complementary section 10' assembled with the standard 10, that any number of these sections may be combined, utilizing similar joining means.

In Figure 3 I have illustrated a modification of the means for joining the standard 10 with a complementary section 10'. In this construction the walls 11' and 12' are provided with perforations corresponding to 24 in the modifications shown in Figures 1 and 2. Insert members 26 are provided in the form of straps, perforated at 26', the apertures corresponding in position to those formed by the perforations 24 in the standard 10 and the complementary section 10'. It is preferred to slightly convexly shape the straps 26 for a purpose which will hereinafter appear.

To assemble the standard 10 and the complementary section 10', screw members 23' arranged for screw engagement with metal parts are passed through the apertures 24 to engage the screw holders 26' in the straps 26. It is preferred to assemble the insert members 26 with the standard 10 to permit the upper portions of the straps or insert members 26 to protrude beyond the end of the standard 10, as shown in Figure 3. Where I form the straps convexly they will be displaced beyond the plane of the walls

11' and 12' so that upon assembling the complementary section 10', the displaced portion of the straps 26 will serve to frictionally hold the parts in removable relationship preliminarily to final adjustment, at which time additional screw members 23' are passed through the perforations in the member 10', to engage the screw holders 26' in the straps 26.

10 In this manner it will be observed that I have provided an all-metal construction with proper clearance provision for the engaging pins of the display shelf elements. Thus, where I make the sections 10 and 10' of exactly the same cross sectional area, the standard forms an extended member with continuous walls and perforations for engaging the display shelf elements.

15 It will thus be observed that I have provided a simple standard construction useful in a display device for combining therewith display shelf elements along the length thereof and which may be used as illustrated in Figure 1 as a display standard when combined with a separable base, and which may be further extended to accommodate the same to any size display element by combining therewith a complementary section. Thus, any number of display shelf elements may be supported upon the standard to obtain any desired display effect in accordance with the nature of the merchandise to be displayed or in accordance with the display area that may be provided.

20 35 Having thus described my invention and illustrated its use, what I claim as new and desire to secure by Letters Patent, is:

25 In a display device, a hollow metal standard section arranged to have combined therewith display shelf elements which embrace the standard and which include display shelf supporting members, said standard including shelf pin and arm engaging orifices; a complementary section for said standard, the side walls thereof forming a smooth and continuous surface with said first section and a filler member disposed interiorly of said section holding said sections in butt joint engagement, one of said sections including an end 30 thereof formed with the metal of a pair of walls bent laterally outwardly to serve as base engaging ears, another of said walls being formed with a downwardly formed base engaging ear.

35 55 In witness whereof I have hereunto signed my name this 22d day of May, 1928.

MATTHEW M. FRIEDEMANN.
